EXTRUSION PRESS

Richard W. Dinzl, Westfield, N. J., assignor to
The Watson-Stillman Co., Roselle, N. J., a corporation of New Jersey

Application September 19, 1938, Serial No. 230,543

23 Claims. (Cl. 207—2)

This invention relates more particularly to improvements in extrusion presses of a type designed to perform an extrusion operation upon a metal charge in the form of a billet.

Important objects of the invention are, to provide such a press designed for improved operation; to provide a billet container of improved design and with an improved mounting to facilitate installation and removal of the container and enable accurate adjustment of the container for the extrusion operation; to provide improved means for charging the container; to provide for shifting of the extrusion plunger transversely in order to afford clearance for charging the container; and to provide an automatic safeguard against operation of the plunger at an improper time.

Other objects of the invention will appear hereinafter.

20 In the drawings,

Fig. 1 is a sectional side elevation of the improved press;

Fig. 2 is an enlarged horizontal section of the line 2—2 of Fig. 1;

25 Fig. 3 is an enlarged vertical detail section on the line 3—3 of Fig. 1;

Fig. 4 is a further enlarged vertical section on the line 4—4 of Fig. 1;

Fig. 5 is a view similar to Fig. 4 but looking 30 in the opposite direction from line 4—4;

Fig. 6 is a diagrammatic view, partly in section, showing the mechanism responsive to shifting of the die-locking blocks to prevent operation of the main control valve for plunger advance

35 at an improper time;

Fig. 7 is an enlarged vertical section on the line 7—7 of Fig. 2, showing the completion of an extrusion operation;

Fig. 8 is an enlarged detail section on the line 40 8—8 of Fig. 7; and

Fig. 9 is an outer face view of the means for adjusting one of the container-supporting rollers.

The press is of a horizontal type designed, in the present instance, for extrusion of rods from

45 metal billets. It is, however, adaptable for other forms of extrusion such as tube extrusion, for example. The press includes horizontally spaced press frame heads 1 and 2 mounted upon a floor or other support and rigidly connected by strain

50 rods 3. A horizontal hydraulic cylinder 4 is formed with the head 2 and contains a ram 5. Head 1 bears the extrusion die means and the ram 5 bears, at its forward end, an extrusion plunger 6. Between the plunger and the die means there is a container unit 7 to receive an

extrusion charge and also receive the plunger 6 when the latter is advanced by the ram for the extrusion operation. For retraction of the ram and plunger there is a pull-back mechanism including two hydraulic cylinders 8 affixed to the 5 head 2, at opposite sides of the cylinder 4. Plungers 9 are fitted to reciprocate in the cylinders 8 and have their rear ends anchored to a cross-head 10. A tubular member 11 is anchored, at its opposite ends to the center of the cross-head and to the ram 5 and is reciprocable through a stuffing box at the rear end of the cylinder 4. There are rods 12 arranged parallel to the plungers 9 and anchored at their forward ends to the cylinder 4. Said rods extend through 15 bores 13 in the crosshead and have stops 14 at their rear ends for engagement by the crosshead to limit retraction of the ram.

The die means includes a cylindrical die holder 15 having a central bore 16 counter-bored at 20 one end to form a seat for the die 17. The die holder is removably fitted in a bore 18 formed partly in the press frame head 1 and partly in a cage member 19 secured to the rear face of said head. Within said bore the die holder is 25 supported with the die in register with a charge-receiving bore 20 in the container 7. For locking the die holder in place there is a pair of opposed locking blocks 21. These are supported by the head 1 and the cage 19 for transverse sliding 30 into and out of operative position. They are received within a peripheral channel 22 in the holder and have opposed semi-cylindrical recesses 23 to receive a neck portion 24 of the holder. The rear faces of the blocks abut walls 35 25 borne by the head 1, and the blocks form abutments for the holder to positively resist extrusion thrust upon the die. Pneumatic mechanism is provided for projecting the blocks into locking position and retracting them. Said 40 mechanism includes two air cylinders 26 affixed to opposite sides of the press frame head 1 and containing pistons 27 with stems 28 connected to the blocks. Air piping is connected to the opposite ends of the air cylinders. Through the 45 operation of valve means, not shown, air pressure in the cylinders 26 is controlled to shift the pistons 27 inward in unison to apply the locking blocks and to shift the pistons outward in unison to withdraw the blocks from the die 50 holder and permit withdrawal of the latter through the outer end of the bore 18.

As shown in Fig. 7, at the completion of an extrusion operation a stub 8 of the extrusion charge remains attached to the die 17. For re- 55

removal of the stub the die holder is drawn forward from the bore 18 to a position in which the stub is located directly beneath a vertically reciprocable block 29 known as a "stub shear" 5 and said block is driven downward to knock off the stub. A guide trough 30 for the extruded product, or rod, is anchored as at 31 to the forward end of the die holder and in alinement with the bore 16 of the holder. Said trough is 10 mounted for sliding longitudinally upon a narrow, elongated table 32 extending forward from the press frame head 1. Pneumatic mechanism is provided for reciprocating the trough and connected die holder. Affixed to the under side of 15 said table there is an air cylinder 33 containing a piston 34 with a rod 35. The latter is operatively connected to the trough, as at 36. Air piping leads to the opposite ends of cylinder 33. Through operation of valve means, not shown, 20 piston 34 is reciprocated to withdraw and reinsert the die holder by shifting the trough 30. The stub shear 29 is hydraulically operated. It is borne by a ram 37 with a piston head 38 reciprocable in a hydraulic cylinder 39 affixed to 25 the press frame head 1. By admission of hydraulic pressure to the upper side of said piston the block 29 is forced downward to knock off the stub, and by admission of hydraulic pressure to the under side of the piston the shear block is 30 retracted. The table 32 bears a stop 40 to limit forward movement of the trough 30 to a position in which the stub is directly beneath the stub shear.

The container unit 7 includes a cylindrical body 41 with a heating jacket 42 surrounding its periphery. Said body has a bore 43 containing a bushing 44. The latter has the charge-receiving bore 20. At its forward end bore 20 is flared slightly, and the die 17 is bevelled to fit 35 in said flare. The unit is mounted for fore-and-aft shifting and also for universal tilting adjustment to dispose its bore 20 in accurate alinement with the die and the extrusion plunger. It is also formed and mounted to facilitate its removal 40 from the press assembly. At its opposite sides 45 the unit is formed with ribs 45 whose under sides form a pair of flat tracks 46 parallel to the bore 20. The strain rods 3 are in rectangular arrangement around the axis of the extrusion plunger, and the container unit is centrally located 50 in the space between the strain rods. A bed 47 underlies the container unit and is clamped, as at 48, upon the lower pair of strain rods. Said bed bears four rollers 49 upon which the tracks 46 rest to support the container unit. 55 Each roller is mounted on the inner end of a shaft 50, and each shaft is mounted in a bearing 51 borne by the bed and located directly over the adjacent strain rod. Each of said shafts has, at its inner end, an eccentrically located 60 journal 52 for its roller. Each shaft also has a radial adjusting arm 53 keyed to its outer end and bearing a locking pin or screw 54. The latter is engageable in a selected one of a plurality of holes 55 in the adjacent side face of the bed and arranged in an arcuate row. Thereby a rotative adjustment of the shaft is retained.

By rotative adjustment of all of the shafts 50 the container unit may be raised or lowered 70 bodily, and by adjustment of selected ones of the shafts the unit may be tiltably adjusted either transversely or longitudinally to dispose its bore 20 in accurate alinement with the die and with the extrusion plunger. Guide cleats 56 engage 75 the ribs 45 to hold the unit upon the rollers. The

ribs and the cleats are correspondingly beveled and the cleats are transversely adjustable upon the bed 47 to accommodate adjustments of the container unit. For adjustment of the cleats there are screws 57 threaded through upstanding lugs 58 on the bed and engaging the outer edges of the cleats. Clamping screws 59 extend downward through transverse slots 60 in the cleats and are screwed into the bed to releasably lock the cleats in position.

Pneumatic mechanism is provided for shifting the container unit back and forth upon its supporting rollers, for a purpose which will be explained hereinafter. Mounted upon the forward face of the press frame head 1, below the bore 18, there is a horizontal air cylinder 61 containing a piston 62. The piston has a rod 63 extending rearwardly through a bore in the head 1 and operatively connected at its rear end to a slide 64. Guides 65 borne by the bed 47 support the slide 20 for fore-and-aft shifting. The slide has a vertical bore 66 and the container unit has at its under side a pin or stud 67 projecting into said bore. Thereby the piston 62 is operatively connected to the container unit. Air piping leads to the opposite ends of the cylinder 61. Through operation of valve means, not shown, air pressure in the cylinder is controlled to shift the piston and container unit back and forth. There is sufficient clearance for the pin 67 within the bore 66 to permit of the aforesaid adjustments of the container unit and permit free withdrawal of the pin along with the container unit for removal of the latter from the assembly.

It is frequently necessary to remove the container unit from the press assembly. Usually that is a difficult operation because of the limited clearance between the strain rods. In some presses it necessitates taking the unit apart for removal. Provision is made in the present press for easy removal of the unit. For that purpose the unit is mounted for easy and quick release at its mounting and the unit is formed so that its maximum transverse dimension is less than the space between the upper pair of strain rods. In preparation for removal of the unit it is required only to release the cleats 56 and withdraw them from the ribs 45. Then the unit may be lifted out bodily between the upper strain rods by hoisting means, not shown, attached to loops 68 at the 30 upper side of the casing. Replacement of the unit will obviously be a simple operation also.

Provision is made for charging the bore 20 of the container while the latter is in normal, operative position and without operation of the hydraulic mechanism for reciprocating the extrusion plunger 6. For that purpose the said plunger is mounted for shifting transversely to a position out of alinement with the bore 20 and there is provided a charging plunger 69 pneumatically operable when plunger 6 is in that displaced position to force a charge into the bore. Mounted upon the forward end of the ram 5 for reciprocation with it there is a rocker member 70 which bears the plunger 6. This rocker member is mounted to swing transversely on a shaft 71, affixed to the ram, parallel to the ram axis and spaced to one side. The rocker bears a bushing 72 in which the rear end portion of the plunger is fitted. At its rear end said bushing has a 70 countersunk seat for a flange or head 73 upon the rear end of the plunger. A block 74, fitted in a countersunk seat at the forward end of the ram, forms a back abutment for said plunger head. The rocker has a forked arm 75 extending out-

ward beyond the shaft 71 and bearing a shaft 76 on which there is a roller 77. At the opposite side of the plunger the rocker has an arcuate flange 78. A guide bracket 79 is mounted upon the forward end of the ram and forms a channel slidably receiving the flange 78.

There is pneumatic means for operating the rocker 70. A cross beam 80 is clamped to the upper pair of strain rods. An air cylinder 81 is mounted upon said beam in an oblique position and contains a piston 82. The piston has a rod 83 extending downwardly and outwardly and bearing a head 84 at its lower end for engagement with the roller 77. The cylinder bears a tubular guide 85 for the piston rod. Piping leads to opposite ends of the cylinder. Through operation of valve means not shown fluid pressure in the cylinder is controlled to reciprocate the piston and head 84. By advance of said head the rocker and the extrusion plunger are swung to the position indicated by dotted lines in Fig. 4. There the dotted plunger 6 is in a position out of alignment with the container bore 20 and the charging plunger 69 so that the latter may be advanced to force a charge into the bore. Upon retraction of head 84 the rocker and plunger gravitate to normal position. The plunger is held by the rocker for parallel movement into and out of its operative position. The cylinder 81 is mounted in a fixed position so that the roller 77 is beneath the plunger head 84 only when the ram is fully retracted. The plunger 6 is accurately supported in operative position by engagement of the lower edge of the flange 78 with a stop shoulder on the guide bracket 79.

Charging plunger 69 extends through the ram 5, along the axis of the ram, and is slidably fitted within the tubular member 11 and within a bore in the block 74 at the forward ends of the ram. At its rear end the plunger bears a piston 86 fitted to reciprocate within an air cylinder 87. Said cylinder and the crosshead 10 are both fixed to a base 88 mounted to slide upon a narrow, elongated table 89, so that the said base and cylinder reciprocate with the ram 5 and the crosshead. Air piping leads to opposite ends of cylinder 87. Through operation of valve means, not shown, air pressure is controlled in the cylinder for advancing and retracting the plunger 69. Normally said plunger is disposed back of the extrusion plunger 6. When the latter is swung out of the way plunger 69 may be advanced to force a charge into the container.

A charge carrier is provided to receive a billet and dispose it in alignment with the bore 20 of the container, for insertion by the plunger 69. The container comprises an arcuate, trough-like member 90. A pair of radial arms 91 have their lower ends pivotally connected, as at 92, to the bed 47 and their upper ends rigidly connected to the carrier. Thereby the carrier is supported for rocking transversely from a charge-receiving position, shown by full lines in Fig. 4, to a charge delivery position indicated by dotted lines in said view. The carrier-supporting arms 91 include a turnbuckle structure 93 for adjusting their length, for support of the carrier in position to dispose the billet in accurate alignment with the bore 20. This adjustment accommodates the carrier to variations in the diameter of bore 20. For that purpose also, the carrier is formed to receive a billet of maximum size, if required. A smaller billet will center itself in the curved carrier to align with the bore 20. The carrier 75 is rocked between its charge-receiving and charge

delivery positions by pneumatic means. An air cylinder 94 is pivotally supported, as at 95, upon a pedestal 96 to rock about a transverse axis parallel to the axis about which the carrier rocks. A piston 97 reciprocable in said cylinder has a rod pivotally connected at 98 to a connecting structure between the arms 91 and the carrier. Air piping leads to opposite ends of the cylinder. Through operation of valve means, not shown, air pressure in the cylinder is controlled to reciprocate the piston and rock the carrier. In its delivery position the carrier is directly at the entrance of the bore 20. The carrier is disposable at that position after the extrusion plunger has been rocked out of the way to afford clearance.

Reciprocation of the ram 5 and plunger 6 is controlled by a hydraulic valve device 99. This device is manually operable through a lever 100. The latter is operatively connected to a rockable element 101, which in turn operates the valves of the device to control flow to and from the press cylinder 4 and to and from the pull-back cylinders 8. A pipe 102 leads from the valve device to the cylinder 4, and piping 103 leads from the valve device to the pull-back cylinders. The valve device is of a conventional form and it is thought to be unnecessary to illustrate and describe it in detail.

In order to prevent damage to certain parts of the press it is important to prevent advance of the extrusion plunger under hydraulic pressure except when the die-locking blocks 21 are either projected fully to locking position or fully retracted to release position. There is here provided an automatic safeguard against plunger advance at an improper time. For plunger advance the valve lever 100 and the rocker 101 are rocked to the right, with reference to Fig. 6. A locking block 104 is slidably mounted upon the base 105 of the valve device and is shiftable between a locking position beneath the rocker 101 and a release position away from the rocker. When it is beneath the rocker it blocks operation of the rocker for plunger advance. Pneumatic mechanism is provided for operating the locking block 104, and said mechanism is controlled through the die-locking blocks 21.

Each block 21 has, rigid therewith, a laterally extending arm 106 formed with a cam 107 at 50 its under side. Beneath each of said arms there is an air valve 108 mounted in a fixed position. Each valve comprises a casing forming two chambers 109 and 110 and an upwardly seating valve element 111 controlling communication between 55 said chambers. Said valve element has an upwardly projecting stem 112 bearing a roller 113 engageable by the adjacent cam 107. A spring 114 in the chamber 109 constantly urges the valve element to closed position and normally holds the roller in the path of said cam. Piping 115 leads from a compressed air source, not shown, to the valve chambers 109. Piping 116 leads from the valve chambers 110 to a main air valve device 117. The latter comprises an elongated, cylindrical casing 118 containing a multiple-head piston valve 119. This valve is responsive to operation of the valve 108 and controls operation of the locking block 104. Said block has an operating rod 120 bearing a piston 121 reciprocable within an air cylinder 122. A pipe 123 leads from the valve device 117 to the outer end of cylinder 122, and a pipe 124 leads to the inner end of the cylinder. A pipe 125 leads from a compressed air source, not shown,

- to the valve device 111. A spring 126 normally holds the valve 119 in a position to admit air from pipe 125, through ports 127 and 128 to pipe 124, and to vent pipe 123 to atmosphere through ports 129 and 130. Thereby air pressure delivered by the pipe 124 to the inner end of cylinder 122 acts upon piston 121 to hold the locking block 104 in release position, as shown by full lines in Fig. 6.
10. In Fig. 6 the die-locking blocks 21 are shown fully retracted to release position. In that position the valve rollers 113 are at the inner ends of the cams 107 and the springs 114 hold the valves 111 in closed position. As soon as movement of the blocks toward each other to locking position is commenced the cams operate upon the rollers to force the valves 111 to open position against the resistance of their springs 114. Thereby air is admitted from the supply piping 115 to the delivery piping 116. The latter delivers to the opposite end of the valve 119 from that engaged by spring 126, and the delivered air forces valve 119 to the dotted line position, against the spring resistance. In that position 25 of the valve air is exhausted from the inner end of cylinder 122 through pipe 124 and ports 128 and 131. Simultaneously, compressed air is admitted to the outer end of cylinder 122 through supply pipe 125, ports 127 and 129 and pipe 123.
30. Thereby the piston 121 is shifted to move the locking block 104 to locking position beneath the valve rocker 101, as indicated by dotted lines. The cams 107 are of sufficient length to hold the valves 111 open until the die-locking blocks 21 are brought together in full locking position.
35. The cams are then off the rollers 113 so that the springs 114 close the valves 111 to cut-off communication between air supply piping 115 and delivery piping 116. The latter has a restricted exhaust at 132 through which air pressure in the piping bleeds so that the spring 126 can force the valve 119 back to normal position. Valve 119 there reestablishes the air connections previously described for shifting locking block 104 to release position and holding it there. When the die-locking blocks 21 are shifted away from each other to release position the cams 107 immediately open the valves 111 and hold them open until blocks 21 reach full release position. That 45 has the same effect upon the valve-locking block 104 as the closing of the die-locking blocks. Block 104 is forced to locking position and held there until the blocks 21 are fully retracted, whereupon block 104 is retracted to release position.
50. Therefore there can be no operation of the valve lever 100 to cause advance of the extrusion plunger when the die-locking blocks are in any position intermediate full locking position and full release position.
55. In the operation of the press the container may be heated, if required, by placing a burner at the inlet of the jacket 42. Said inlet is located at the under side of the jacket. Starting with the parts of the press in the positions shown in Figs. 1 and 2, the extrusion plunger 6 is swung out of alignment with the container bore 20 and the charging plunger 69 by operation of the piston 82. A heated billet B is placed in the carrier 90 together with a "dummy block" D back of the billet. By 65 operation of the air piston 91 the carrier is then swung to delivery position, disposing the billet and dummy block in alignment with the bore 20. The charging plunger 69 is next advanced, by operation of the air piston 86, to force the billet and dummy block from the carrier and into bore

70. The charging plunger is then retracted by operation of the piston 86, the charge carrier 90 is swung aside to charge-receiving position by operation of piston 91, and plunger 6 is permitted to swing back to operative position by retraction of the piston 82 and plunger head 84.

Having thus charged the container and restored the carrier 90 and plungers 69 and 6 to normal position, the handle 100 of the hydraulic valve device 99 is rocked to cause advance of ram 10 5 and plunger 6 by hydraulic pressure in cylinder 4. At its forward end the ram bears a roller 133 to run upon a grooved track 134 borne by the bed 47, to steady the ram in its movement. The advancing extrusion plunger enters the bore 20, 15 engages the dummy block and forces the latter along the bore to extrude the charge through the die 17, in the form of a rod R which is guided by the trough 30 as it emerges from the bore of the die holder. At the completion of the extrusion 20 operation the die-locking blocks 21 are retracted to release position by operation of the air pistons 27. Then the trough 30 and connected die-holder 15 are moved forwardly by operation of air piston 34 until the trough engages the stop 46. The die 25 is then in a position to dispose the stub S of the extrusion charge directly beneath the stub shear 29, as indicated in Fig. 8 by dotted lines. The stub shear is forced downward, by operation of its piston 38, to knock off the stub, and is then 30 retracted.

After each extrusion operation it is necessary to remove the dummy block and employ another block for the next extrusion operation. That is to prevent overheating and distortion of the 35 block. After a block has been allowed to cool it may be used again. For ejection of the dummy block the container unit 7 is shifted rearward upon its supporting rollers 49 to the position indicated by dotted lines in Fig. 7. This shift of the 40 unit is effected by operation of the air piston 62. As the unit is so shifted the extrusion plunger 6 forces the block out of the bore 20 and it drops through the space between the container unit and the cage member 19.

45. The plunger 6 is next retracted, the container unit 7 and die holder 24 are restored to their operative positions by operation of their respective air pistons 27 and 62, and the die-locking blocks 21 are projected to locking position by 50 operation of their air pistons 27. Thereby the press is prepared for another extrusion operation.

55. What I claim is:

1. An extrusion press comprising opposed spaced press frame heads, transversely spaced strain rods connecting said heads, extrusion die means, abutment means associated with one of said heads and shiftable between an operative position to resist extrusion thrust upon said die means and an inoperative position free from the 60 die means, a fluid pressure cylinder rigid with the other head, a ram reciprocable in said cylinder, a container unit between said heads, associated with said die means and having a bore to receive an extrusion charge, an extrusion plunger connected to said ram for advance thereby into said bore and retractible therefrom, means operable to control reciprocation of the ram and plunger, means to prevent operation of said control means for advance of the ram and plunger when the 70 said abutment means is intermediate its said positions, means supporting the plunger for shifting, when retracted, out of alignment with the container bore, and means for adjusting the container unit relatively to the die means and plunger 75

to position its bore accurately for an extrusion operation, the container being formed and mounted for removal bodily from the press assembly through the space between a pair of said strain rods.

2. An extrusion press comprising opposed spaced press frame heads, transversely spaced strain rods connecting said heads, extrusion die means, abutment means associated with one of said heads and shiftable between an operative position to resist extrusion thrust upon said die means and an inoperative position free from the die means, a fluid pressure cylinder rigid with the other head, a ram reciprocable in said cylinder, a container unit between said heads, associated with said die means and having a bore to receive an extrusion charge, an extrusion plunger connected to said ram for advance thereby into said bore and retractable therefrom, means operable to control reciprocation of the ram and plunger, means to prevent operation of said control means for advance of the ram and plunger when the said abutment means is intermediate its said positions, and means supporting the plunger for shifting, when retracted, out of alignment with the container bore, the container being formed and mounted for removal bodily from the press assembly through the space between a pair of said strain rods.

3. An extrusion press comprising horizontally opposed spaced press frame heads, transversely spaced horizontal strain rods connecting said heads, extrusion die means, abutment means associated with one of said heads and shiftable between an operative position to resist extrusion thrust upon said die means and an inoperative position free from the die means, a horizontal fluid pressure cylinder rigid with the other head, a ram reciprocable in said cylinder, a container unit between said heads, associated with said die means and having a bore to receive an extrusion charge, an extrusion plunger connected to said ram for advance thereby into said bore and retractable therefrom, means operable to control reciprocation of the ram and plunger, means to prevent operation of said control means for advance of the ram and plunger when the said abutment means is intermediate its said positions, and means supporting the plunger for shifting when retracted out of alignment with the container bore, the container being formed and mounted for upward removal bodily from the press assembly through the space between a pair of said strain rods.

4. An extrusion press comprising horizontally opposed spaced press frame heads, transversely spaced horizontal strain rods connecting said heads, a fluid pressure cylinder rigid with one of said heads, an extrusion plunger operable by fluid pressure in said cylinder, a container unit between said heads and having a bore to receive an extrusion charge and to receive said plunger, a pair of said strain rods being arranged around the upper side of the container unit, said unit having transversely spaced tracks facing downward and parallel to the strain rods, two fore-and-aft pairs of rollers engaging said tracks to support the unit for fore-and-aft shifting, individual shafts bearing said rollers and having eccentric journals for the rollers, means supporting said shafts for individual rotative adjustment to raise and lower the rollers for adjustment of the unit to position its bore accurately for an extrusion operation, and guides to releasably hold the unit upon said rollers and ad-

justable to permit said adjustment of the unit, the unit being formed for upward removal bodily through the space between said pair of strain rods.

5. An extrusion press comprising horizontally opposed spaced press frame heads, transversely spaced horizontal strain rods connecting said heads, a fluid pressure cylinder rigid with one of said heads, an extrusion plunger operable by fluid pressure in said cylinder, a container unit between said heads and having a bore to receive an extrusion charge and to receive said plunger, a pair of said strain rods being arranged around the upper side of the container unit, said unit having transversely spaced tracks facing downward and parallel to the strain rods, two fore-and-aft pairs of rollers engaging said tracks to support the unit for fore-and-aft shifting, individual shafts bearing said rollers and having eccentric journals for the rollers, and means supporting said shafts for individual rotative adjustment to raise and lower the rollers for adjustment of the unit to position its bore accurately for an extrusion operation, the unit being formed for upward removal bodily through the space between said pair of strain rods.

6. An extrusion press comprising an extrusion charge container and extrusion plunger mounted for relative advance for an extrusion operation and retraction to free the plunger from the container, means supporting said plunger for shifting out of alignment with the container when free therefrom, to provide clearance for insertion of a charge into the container, and a charge carrier mounted for shifting between a charge-receiving position and a charge-delivery position, said carrier being shiftable to the latter position to dispose a charge in alignment with the container for insertion when the extrusion plunger is shifted out of alignment with the container, and means operable when the extrusion plunger is out of alignment with the container and said carrier is in its delivery position to force a charge from the carrier and into the container.

7. An extrusion press comprising an extrusion charge container and an extrusion plunger mounted for relative advance for an extrusion operation and retraction to free the plunger from the container, means supporting said plunger for shifting out of alignment with the container when free therefrom, to provide clearance for insertion of a charge into the container, and a charge carrier mounted for shifting between a charge-receiving position and a charge-delivery position, said carrier being shiftable to the latter position to dispose a charge in alignment with the container for insertion when the extrusion plunger is shifted out of alignment with the container.

8. An extrusion press comprising an extrusion charge container and an extrusion plunger mounted for relative advance for an extrusion operation and retraction to free the plunger from the container, a charging plunger mounted in alignment with the container and normally back of the extrusion plunger, means supporting the extrusion plunger for shifting, when free from the container, out of alignment with the container and the charging plunger, and a charge carrier shiftable between a charge-receiving position and a charge-delivery position, said carrier being shiftable to the latter position to dispose a charge in alignment with the container and the charging plunger being then operable to

advance it to force the charge from the carrier and into the container.

9. An extrusion press comprising an extrusion charge container and an extrusion plunger 5 mounted for relative advance for an extrusion operation and retraction to free the plunger from the container, a charge-inserting plunger mounted in alinement with the container and normally back of the extrusion plunger, and means 10 supporting the extrusion plunger for shifting, when free from the container, out of alinement with the container to provide clearance for advance of the charge-inserting plunger to force a charge into the container.

15. 10. An extrusion press comprising an extrusion charge container and an extrusion plunger mounted for advance of the plunger into the container and retraction therefrom, a fluid pressure operated ram for reciprocating the extrusion 20 plunger, and means supporting said plunger on said ram for shift of the plunger thereon, when retracted, to a position out of alinement with the container to provide clearance for inserting a charge into the container.

25. 11. An extrusion press comprising an extrusion charge container and an extrusion plunger mounted for advance of the plunger into the container and retraction therefrom, a fluid pressure operated ram for reciprocating the extrusion 30 plunger, means supporting said plunger on said ram for shift of the plunger thereon, when retracted, to a position out of alinement with the container to provide clearance for inserting a charge into the container, and fluid pressure operated means for shifting the extrusion 35 plunger out of alinement with the container.

40. 12. An extrusion press comprising an extrusion charge container and an extrusion plunger mounted for advance of the plunger into the container and retraction therefrom, a fluid pressure operated ram for reciprocating the extrusion plunger, and means pivotally supporting the plunger for transverse parallel rocking, when retracted, to a position out of alinement with 45 the container to provide clearance for insertion of a charge into the container.

45. 13. An extrusion press comprising an extrusion charge container and an extrusion plunger mounted for advance of the plunger into the container and retraction therefrom, a fluid pressure operated ram for reciprocating said plunger, means supporting the plunger for transverse parallel rocking, when retracted, to a position out 50 of alinement with the container, fluid pressure operated means for rocking the extrusion plunger out of alinement with the container, a charging plunger in alinement with the container and normally back of the extrusion plunger and mounted to reciprocate axially through said ram, fluid pressure operated means for operating said 55 charging plunger, a charge carrier pivotally mounted for rocking between a charge-receiving position and a charge-delivery position, said carrier being shiftable to the latter position when the retracted extrusion plunger is out of alinement with the container, to dispose a charge in 60 alinement with the container for insertion into the container by advance of the charging plunger, and fluid pressure operated means for rocking 65 the charge carrier.

70. 14. An extrusion press comprising an extrusion charge container and an extrusion plunger mounted for relative advance for an extrusion operation and retraction to free the plunger from 75 the container, and means supporting said plunger-

er for shifting out of alinement with the container when free therefrom, to provide clearance for insertion of a charge into the container.

15. An extrusion press comprising extrusion die means and an extrusion plunger mounted 5 for relative advance for extrusion and retraction for charging, means operable to control said advance, abutment means shiftable between an operative position to resist extrusion thrust upon the die means and an inoperative position free 10 from the die means, and means responsive to shift of said abutment means between its said positions to prevent operation of said control means for said advance when said abutment means is intermediate said positions. 15

16. An extrusion press comprising extrusion die means and an extrusion plunger mounted for relative advance for an extrusion operation and retraction for charging, means operable to control said advance, abutment means shiftable 20 between an operative position to resist extrusion thrust upon the die means and an inoperative position free from the die means, and fluid pressure operable means responsive to shift of said abutment means between its said positions to 25 prevent operation of said control means for said advance when said abutment means is intermediate said positions.

17. An extrusion press comprising extrusion die means and an extrusion plunger mounted for 30 relative advance for an extrusion operation and retraction for charging, fluid pressure operable means for effecting said advance, valve means operable to control fluid pressure for said advance, abutment means shiftable between an operative position to resist extrusion thrust upon the die means and inoperative position free from the die means, a lock for said control valve means, and fluid pressure operable means responsive to shift of said abutment means between its said 35 positions to operate said lock to prevent operation of the control valve means for said advance when the abutment means is intermediate said positions.

18. An extrusion press comprising extrusion die 45 means and an extrusion plunger mounted for relative advance for an extrusion operation and retraction for charging, means operable to control said advance, abutment means shiftable between an operative position to resist extrusion 50 thrust upon the die means and an inoperative position to free the die means, and means to prevent operation of said control means for said advance when said abutment means is intermediate its said positions. 55

19. An extrusion press comprising a pair of press frame heads in horizontally opposed spaced relation, spaced parallel horizontal strain rods connecting said press heads, a fluid pressure cylinder rigid with one of said heads, an extrusion plunger operable by fluid pressure in said cylinder, and a container unit mounted between said heads and having a bore to receive an extrusion charge and to receive said plunger, the strain rods being arranged around said unit and 60 the unit being formed and mounted for upward removal bodily from the press assembly through the space between a pair of the strain rods. 65

20. An extrusion press comprising an extrusion plunger, a container having a bore to receive an 70 extrusion charge and to receive said plunger for extrusion of the charge, means supporting said container for shifting longitudinally of the plunger, for the purpose set forth, and means for adjusting the container vertically and for tiltably 75

adjusting it both transversely and longitudinally to position its bore accurately for an extrusion operation.

21. In an extrusion press comprising an extrusion plunger, and a container having a bore to receive an extrusion charge and to receive said plunger for extrusion of the charge, a charge carrier, means pivotally supporting the carrier for rocking transversely of said bore between a charge-receiving position and a charge delivery position to dispose the charge in alignment with the bore for insertion into the latter, and means for adjusting said carrier-supporting means to dispose the charge in accurate alignment with the bore.

22. In an extrusion press comprising an extrusion plunger, and a container having a bore to receive an extrusion charge and to receive said plunger for extrusion of the charge, a charge

carrier, supporting arms for said carrier pivotally supported at their ends remote from the carrier for rocking of the latter between a charge-receiving position and charge-delivery position to support the charge in alignment with the bore for insertion into the bore, and means for longitudinally adjusting the length of said arms to position the carrier for accurate alignment of the charge with the bore.

23. In an extrusion press comprising an extrusion plunger, and a container having a bore to receive an extrusion charge and to receive said plunger for extrusion of the charge, a charge carrier, and means pivotally supporting the carrier for rocking transversely of said bore between a charge-receiving position and a charge delivery position to dispose the charge in alignment with the bore for insertion into the latter.

RICHARD W. DINZL.
